CALCULATING-MACHINE.

1,223,419.

Specification of Letters Patent. Patented Apr. 24, 1917.

Application filed February 17, 1916. Serial No. 78,733.

To all whom it may concern:

Be it known that I, ARTHUR PENTECOST, a subject of the King of England, residing at East Orange, Essex county, New Jersey, have invented new and useful Improvements in Calculating-Machines, of which the following is a specification.

This invention relates to carriage locking devices, and more particularly to improvements upon a combined tabulating and minutely adjustable space bar mechanism.

Heretofore, it has been customary to provide a fixed tabulating bar having notches entered by a stop finger projecting from a rod journaled on the traveling paper carriage, and controlled by a finger piece. A spring normally maintains the stop finger in engagement with the stationary tabulating bar. Turning the rod against the tension of the spring, lifts the finger out of the notch to enable the carriage to be shifted from column to column, and a further turning of the rod, cams an eccentric, fixed on the rod, against the carriage-supporting casting or a bar thereon to hold the carriage where adjusted in any position intermediate the notches.

The contact of the eccentric with the rigid carriage casting not only scores the casting, but the pressure exerted by the eccentric against the casting tends to spring or strain the carriage out of the carriage ways to the injury of the ball races.

Furthermore, the presence of oil or other lubricant on the rubbing plate or casting gripped by the eccentric, prevents the eccentric from taking a firm hold, especially where the stationary plate has been scored, thus reducing the efficiency of the lock and with a consequent liability of the accidental displacement of the carriage, due to the vibration set up when operating the machine, for instance.

In the present invention, the tabulating bar is mounted on the carriage and carries one or more stops thereon, which coat with a stationary abutment.

One of the objects of the invention is to provide an improved and simple means to enable the carriage to be adjusted to and held firmly in any position intermediate the points at which the tabulating stops are set,

for the purpose of printing in special columns, for example, without straining the carriage or its support, and without injury thereto.

To these ends, I have provided a minutely adjustable column spacing bar, and a dog operable independently of the tabulating mechanism, to coat therewith, the operation of setting the dog to active position, also disabling the tabulating mechanism, and vice versa.

Either the dog or the minute space bar, or both, are preferably serrated to avoid any liability of slippage and consequent shifting of the carriage.

Another object of this invention is the provision of simple and improved means to facilitate the relative adjustment of the tabulating bar and stops, which arrest and hold the carriage at the desired and predetermined points, without the use of tools or the disengagement of the stops from the stationary abutment with which they engage.

In setting up the tabulating stops to arrest the carriage when the various columns of a form arrive at the printing point, the operator, after inserting the form or work sheet in the machine, has been in the habit of releasing the active tabulating stop from the stationary abutment by rocking the bar, through the usual finger piece, against the tension of the usual restoring spring, and then shifting the carriage endwise until the first column in which amounts are to be listed, is brought to the printing point, whereupon he loosens the nearest tabulating stop from its bar by means of a tool, and slides it along the bar until the stop registers with the abutment. After tightening the fastening which secures the stop to the tabulating bar, he may free the bar to the action of its spring to assure himself that the stop is correctly placed, after which he repeats the foregoing operation to set other stops in position to lock the carriage at corresponding points in its travel, to print in other columns on the form.

It is more convenient in thus setting the stops for the operator to face the back of the machine, and the entire operation requires some time and labor to perform.

In my invention time and labor consumed

in adjusting the machine for any form, are materially reduced and the operator remains in front of the machine in position to start his work immediately upon the completion 5 of the adjustment, and without having to exert himself.

To these and other ends, therefore, my invention includes certain novel features and combinations of parts, all of which will be 10 more fully set forth hereinafter and particularly pointed out in the claims.

In the drawings, Figure 1 is a rear view of one end of a traveling carriage, of the well known Wales calculating machine, 15 equipped with one embodiment of the invention;

Fig. 2 is a cross sectional view through the carriage, showing a tabulating stop in effective position, the minutely adjustable 20 column spacing mechanism being idle;

Fig. 3 is a similar view, showing the minutely adjustable column spacing mechanism effective and the tabulating mechanism in idle position;

Fig. 4 is a detail plan of the locking dog for the minute space bar, in idle position relatively to the fragment of the bar;

Fig. 5 is a similar view, showing the dog in active position; and

Fig. 6 is a detail, showing the connection between the tabulating and minutely adjustable column space bars.

A carriage support or casting 2067 (Fig. 2), secured by bolts 1155 to the side frames 35 967 of a Wales calculating machine, is provided with ways 2067^a, between which travels the slide 2065 forming part of the carriage. Rollers 1191 interposed between the adjacent edges of the slide and the ways, 40 respectively, enable the slide to be readily shifted along the ways.

An axle 2004 (Figs. 1 and 2), journaled in end plates 2010 secured to the opposite ends of the slide, supports the usual platen 45 2094, equipped with the customary line space ratchet 2020, a line space detent star wheel 1117 being fixed to turn with the axle.

Suitable pressure rolls 2097 and 2097^a (Fig. 2), contact the platen to hold the paper 50 thereagainst and enable it to be fed step by step as the platen is turned.

The foregoing is not claimed in this application, and forms a part of the invention only in so far as it is combined with the 55 novel features hereinafter set forth.

The traveling carriage permits the respective columns on the work sheet inserted around the platen, to be brought to the printing point, to enable amounts to be listed 60 in parallel columns.

Tabulating mechanism to arrest and hold the carriage, when the desired column has been brought to the printing point, comprises a tabulating bar 2092 1/4 (Figs. 1, 2 65 and 3) toothed along its upper edge.

Gudgeons 2093 (Fig. 6) secured to the opposite ends of the bar, journal in the end plates 2010 to shiftably support the bar.

Tabulating stops 2018 1/4 (Figs. 1, 2 and 3) mounted on the bar coat with an abutment 2091 1/2 secured to a fixed part of the machine, as the carriage way 2067^a, to arrest the carriage where adjusted. These stops, of which one or more may be used, 70 each comprise a yoke loosely embracing the tabulating bar 2092 1/4 from beneath, the upper end of the yoke being closed by a toothed block 2092 1/2, whose teeth are adapted to mesh with the teeth on the tabulating bar to secure the stop to the bar. A spring 2080, one end of which encircles and 75 is held in place by a combined spring retainer and stop 2055 1/4, projecting upwardly between the arms of the yoke, presses against a guard plate 2021 1/4 loosely held 80 between the arms of the yoke, and in sliding contact with the smooth lower edge of the tabulating bar, to releasably maintain the teeth of the block 2092 1/2 in mesh with the teeth of the tabulating bar. 85

A tooth or stop 2018 1/4^a projecting from the inner arm of the tabulating yoke, seats in a vertical recess 2091 1/2^a formed in the abutment 2091 1/2, to lock the carriage where adjusted, the stop tooth being held in 90 its seat by a restoring spring 1185, (Fig. 1), one end of which is fixed to a stud 2051 1/8 projecting from one of the gudgeons 2093, the opposite end of the spring being connected to a post 2058 1/2 secured to a part 95 of the carriage slide 2065.

A finger lever 2022 1/2 fastened by a hub 2031 to the projecting end of one of the gudgeons 2093, extends upwardly to a position convenient to the operator, the lever being 105 slotted, as at 2022 1/2^a, (Fig. 2) to embrace the platen axle 2004, which serves as a stop to arrest the throw of the lever in either direction. Rocking the lever rearwardly rocks the tabulating bar against the tension of the 110 restoring spring 1185, to disengage the active stop 2018 1/4 from the abutment 2091 1/2 to enable the carriage to be shifted in either direction to bring the desired column to the printing point. Releasing the lever, frees 115 the tabulating bar to the action of its restoring spring 1185, and as soon as the carriage in its travel, brings the next stop to registry with the abutment, the spring snaps the stop into engagement therewith to lock 120 the carriage where adjusted. Should a stop have been set to arrest the carriage in any column which it is desired to skip, the operator merely continues to hold the lever in operated position while the carriage is shifted until such column has passed the printing point, after which the lever may be released. 125

The opposite ends of the abutment are 130 reversely inclined to enable the tooth 2018 1/4^a

of the stop, when the carriage is shifted in either direction, to ride up the adjacent incline until it registers with the recess 2091 1/2^a in which it is seated by the spring 5 1185.

One of the important advantages of this tabulating mechanism, resides in the ease with which the adjustments are made for arresting the carriage at various points in its 10 travel. Assume that the carriage is at its right hand limit of travel, where it is locked by the stop 2018 1/4 at the left hand end of the tabulating bar.

The operator, after inserting the column- 15 ruled work sheet around the platen, while maintaining his position in front of the machine, and without touching the release lever 2022 1/2, reaches behind the carriage and presses upwardly on the active stop. The 20 lower end of the stop carries oppositely ex- tending inclined lips 2018 1/4^b to form a finger rest. Pressing upwardly on the stop shifts it transversely of the bar 2092 1/4, compressing the spring 2080 until the spring 25 retainer post 2055 1/4 strikes the guard plate 2021 1/4, which contacts the tabulat- 30 ing bar at all times, and arrests further travel of the stop. The arms of the yoke slide relatively to the guard plate, and lift the toothed block 2092 1/2 out of mesh with the tabulating bar 2092 1/4, thus disengaging the tabulating bar and stop preparatory to a relative adjustment thereof.

The distance through which the stop can 35 be shifted transversely of the bar is not sufficient to disengage the stop tooth 2018 1/4^a from its seat 2091 1/2^a in the abutment 2091 1/2, the effective area of which is large enough to maintain engagement with the 40 stop tooth throughout its transverse travel.

The operator, while holding the stop 2018 1/4 disengaged, with his other hand merely slides the carriage until the desired 45 column is brought to printing position, whereupon he frees the stop to the action of its spring 2080, which immediately reengages the toothed block 2092 1/2 with the toothed tabulating bar 2092 1/4. The release lever 2022 1/2 is now operated to dis- 50 engage the tabulating stop from the abut- ment, the carriage slid endwise to bring the next column to the printing point, the lever 2022 1/2 being freed as soon as the adjusted stop 2018 1/4 has passed out of registry 55 with the abutment, and the foregoing procedure repeated to adjust the second stop for the second column.

It will be seen that the carriage and tabulating bar are adjusted relatively to the stop 60 instead of the stop being adjusted along the tabulating bar as is usual, and that the preferred adjustment is readily accomplished, no wrenches or other tools being required, nor is it necessary for the operator to move 65 from in front of the machine. The tabulat-

ing stop maintains its engagement with the abutment throughout the adjustment of the carriage for any particular column, and the necessity for try outs or preliminary adjustments of the stops is reduced to a minimum, 70 the operator being able to quickly determine the exact point at which the stop should be locked to the tabulating bar to arrest the carriage in proper position with the desired column at the printing point. 75

The tabulating mechanism is generally set for the column ruled form most frequently used, and it is desirable to leave the tabulating mechanism undisturbed, so that each time such form is inserted, the tabulating 80 mechanism will properly arrest the carriage, without re-adjustment.

Occasionally, however, it is desired to list infrequent amounts in one column, or to list amounts on a form having a different column arrangement, in order to enable the carriage to be locked with the desired columns at the printing point, without changing the tabulating stops adjusted for the more commonly used form, I provide what I term a minutely 85 adjustable space bar mechanism, whereby the carriage can be locked at any desired point in its travel with a greater degree of accuracy and finer adjustment than is possible with the tabulating mechanism above described, enabling the operator to print amounts in the exact place in the column, 90 where they should appear.

Friction locks for this purpose have hitherto been employed, but my invention provides a simple and more efficient means for this purpose. 100

In my invention, the minutely adjustable space bar 2092 1/8 (Figs. 1, 2 and 3), preferably travels with the carriage, it being 105 conveniently supported by the lower ends of depending arms 2023 1/2 secured by screws 2060 (Figs. 1 and 6) to the tabulating bar 2092 1/4. The minute space bar thus partakes of the endwise and rocking movements 110 of the tabulating bar.

A dog or lock 2025 1/4 pivoted 2050 7/8 to a bracket 2025 fastened to a stationary part of the machine, as the lower carriage way or rail 2067^a, has a toothed jaw 2025 1/4^a turned 115 upwardly to lie opposite the outer edge of the minute space bar, which is preferably serrated, as at 2092 1/8^a.

A spring 2080 1/8 normally holds the dog 120 in idle position.

An operating lever 2025 1/8 (Figs. 1, 4 and 5), pivoted at 2050 1/8 to the bracket 2025, carries a follower, as a roll 2046 1/4 intermediate its ends. The follower normally rests in a recess 2025 1/4^b formed at one end 125 of a cam face 2025 1/4^c formed along one edge of the dog.

In using this minute, column spacing device, the operator, after inserting the special form in the machine, merely reaches behind 130

the carriage and throws the operating lever 2025 1/8 from the idle position shown in Fig. 4 to the active position shown in Fig. 5, to cause the follower 2046 1/4 to ride up the cam or inclined face 2025 1/4° of the dog 2025 1/4 until it seats in a terminal recess 2025 1/4°, and locks the dog in effective position against the tension of spring 2080 1/8. The follower, as it rides up the inclined face, 19 first forces the dog inwardly to bring its toothed jaw 2025 1/4° against the outer serrated edge of the minute space bar 2092 1/8, and then rocks the latter inwardly.

The tabulating bar 2092 1/4 with its stop 15 2018 1/4, because of its connection with the minute space bar, through the arms 2025 1/2, is thereby rocked outwardly against the tension of the restoring spring 1185 to disengage the stop from its abutment 2091 1/2 20 and thus disable the tabulating mechanism.

The carriage is locked against shifting as soon as the serrations of the dog mesh fairly 25 with those on the minute space bar, and prior to the disengagement of the stop from its abutment.

The releasing lever 2022 1/2, being fixed to the tabulating bar, rocks therewith when the bar 2092 1/4 is shifted outwardly by the pressure of the dog 2025 1/4 against the 30 minute space bar 2092 1/8, but the effective throw of the dog is arrested by the contact of the edge 2025 1/4° of the dog with the bracket 2025 (Fig. 5) before the forward end of the slot 2022 1/2° of the lever 2022 1/2 35 contacts the platen axle 2004, which axle positively limits the distance through which the tabulating mechanism can be rocked. Thus the minute space bar is capable of an additional inward movement, sufficient to 40 disengage itself from the dog after the dog has reached the end of its effective throw. This arrangement permits the operator to release the minute space bar from the dog while the latter is in active position, by 45 rocking the release lever 2022 1/2 to the limit of its rearward stroke, to enable the carriage to be adjusted in either direction to bring the desired special column to the printing point, after which the lever is released and 50 the restoring spring 1185 returns the minute space bar into mesh with the dog. The fine serrations afford the possibility of very accurate adjustments of the carriage and column ruled forms relatively to the 55 printing point.

By shifting the operating lever 2025 1/8 in the opposite direction, the follower 2046 1/4 rides down the incline 2025 1/4°, freeing the dog to the action of its releasing 60 spring 2080 1/8, which returns the dog to idle position, thus disabling the minutely adjustable space bar mechanism and releasing the tabulating mechanism to the action of its restoring spring 1185, which immediately rocks the tabulating bar and its stop

back to effective position relatively to the abutment 2091 1/2.

Obviously, the positions of the minute space bar and its locking mechanism might be reversed relatively to the carriage and machine, without sacrificing any of the advantages of the structure as herein set forth.

The dog 2025 1/4 engages the minute space bar 2092 1/8 positively, there being no liability of the carriage accidentally shifting 75 when the dog is active.

Changes may be made in the form and arrangement of the several parts set forth without departing from the spirit and scope of this invention.

What I claim as new, is:—

1. In a traveling carriage, the combination of a tabulating and minutely adjustable spacing mechanism, comprising a tabulating bar shiftably mounted on the carriage; 85 a stop on the bar, the bar and stop being relatively adjustable; a stationary abutment with which the stop coacts; a minutely adjustable space bar connected with the tabulating bar and traveling with the carriage; 90 and means to releasably engage the minute space bar, to disable the stop and lock the carriage where adjusted.

2. The combination with a traveling carriage; a stationary abutment; a tabulating 95 mechanism shiftably mounted on the carriage; and adapted to coact with the abutment; of a minutely adjustable space bar connected with the tabulating mechanism; and a dog, the action of which against the 100 minute space bar, shifts the tabulating mechanism to ineffective position, and locks the carriage where adjusted.

3. The combination with a traveling carriage; a stationary abutment; a tabulating 105 mechanism shiftably mounted on the carriage; and adapted to coact with the abutment; of a minutely adjustable space bar connected with the tabulating mechanism; a dog, the action of which against the 110 minute space bar, shifts the tabulating mechanism to ineffective position, and locks the carriage where adjusted; and means to control the dog.

4. The combination with a traveling carriage; a stationary abutment; and a tabulating mechanism shiftably mounted on the carriage; and adapted to coact with the abutment; of a serrated, minutely adjustable space bar; a serrated dog; and means 120 to force the dog against the minute space bar to disable the tabulating mechanism and lock the carriage where adjusted.

5. The combination with a traveling carriage; a stationary abutment; and a tabulating 125 mechanism shiftably mounted on the carriage; and adapted to coact with the abutment; of a minutely adjustable space bar connected with the tabulating mechanism; a dog, the action of which against the 130

minute space bar, shifts the tabulating mechanism to ineffective position, and locks the carriage where adjusted; and means to control the dog, the dog having a seat entered by the operating means to hold the dog effective.

6. The combination with a traveling carriage; a stationary abutment; and a tabulating mechanism shiftably mounted on the carriage; and adapted to coact with the abutment; of a minutely adjustable space bar; a dog to coact therewith; means normally tending to hold the dog idle; and means to force the dog against the minute space bar to shift the tabulating mechanism to ineffective position, and lock the carriage where adjusted.

7. The combination with a traveling carriage; a stationary abutment; and a tabulating mechanism shiftably mounted on the carriage; and adapted to coact with the abutment; of a minutely adjustable space bar; a dog to coact therewith; means normally tending to hold the dog idle; and means to force the dog against the minute space bar to shift the tabulating mechanism to ineffective position, and lock the carriage where adjusted, the last mentioned means being operable to hold the dog in active position until released.

8. The combination with a traveling paper carriage; of a combined tabulating and minutely adjustable spacing mechanism, including a tabulating bar shiftably mounted on the carriage; a stop mounted on the bar; the stop and bar being relatively adjustable; means to releasably lock the stop to the bar; an abutment with which the tabulating stop coöperates to lock the carriage in adjusted position; and yielding means to maintain the engagement between the abutment and the tabulating stop; a minutely adjustable space bar connected with the tabulating bar; a lock adjustable to coöperate with the minute space bar, the lock, by its engagement with the minute space bar, adapted to rock the tabulating bar against the action of the yielding means, to disengage the tabulating stop from its abutment, and to lock the carriage where adjusted; and means to control the lock.

9. In a traveling carriage, the combination with a rocking tabulating bar; stops mounted thereon, the stops and bar being relatively adjustable; a stationary abutment with which the adjustable stops singly coöperate; and restoring means to maintain the stops in effective engagement with the abutment; of a minutely adjustable space bar carried by the tabulating bar; a normally ineffective dog operable independently of the tabulating bar, to coöperate with the minute space bar to rock the stops to ineffective position, and to lock the carriage in any of its positions; and means to

render the dog effective or ineffective at will.

10. In a traveling carriage, the combination with a rocking tabulating bar; stops mounted thereon, the stops and bar being relatively adjustable; a stationary abutment with which the adjustable stops singly coöperate; and restoring means to maintain the stops in effective engagement with the abutment; of a minutely adjustable space bar carried by the tabulating bar; a normally ineffective dog operable independently of the tabulating bar, to coöperate with the minute space bar to rock the stops to ineffective position, and to lock the carriage in any of its positions; and controlling means to render the dog effective, or to disable the dog and free the tabulating stops to the action of their restoring means.

11. The combination with a traveling carriage; a tabulating stop bar journaled in the carriage; a stop mounted on the bar, the stop and bar being relatively adjustable; a stationary abutment with which the stop coöperates; and a spring to maintain the stop in engagement with the abutment; of a minutely adjustable space bar; a dog to coöperate with the minutely adjustable space bar to lock the carriage where adjusted; and controlling means operable through the dog to cause the latter to disable the tabulating stop and to lock the carriage, or to disable the dog and free the stop to the action of the spring.

12. In a traveling carriage, the combination with a stationary abutment; a tabulating stop bar; a stop on the tabulating bar, adapted to coöperate with the abutment; the tabulating stop bar and its stop being shiftable relatively to the abutment; of a minutely adjustable space bar connected with the tabulating bar; a dog to coöperate with the minute space bar; and means to render the dog effective to shift the tabulating bar and its stop to ineffective position, relatively to the abutment, and to lock the carriage where adjusted.

13. In a traveling carriage, the combination with a stationary abutment; a tabulating stop bar; and a stop on the tabulating bar, adapted to coöperate with the abutment; the tabulating stop bar and its stop being shiftable relatively to the abutment; of a minutely adjustable space bar connected with the tabulating bar; a dog to coöperate with the minute space bar; and means to render the dog effective to shift the tabulating bar and its stop to ineffective position, relatively to the abutment, and to lock the carriage where adjusted, and to release the dog and free the tabulating bar and its stop to enable their return to effective position.

14. The combination with a traveling carriage; a stationary abutment; a tabulating

- stop bar shiftably mounted on the carriage; a stop carried on the bar, and adapted to coöperate with the abutment, the stop and bar being relatively adjustable; and means to retain the stop and abutment in coöperative position; of a minutely adjustable space bar connected with the tabulating stop bar; and a dog operable upon the minute space bar to disable the tabulating stop bar and its stop, and to lock the carriage where adjusted.
15. The combination with a traveling carriage; a stationary abutment; a tabulating stop bar shiftably mounted on the carriage; a stop carried on the bar, and adapted to coöperate with the abutment, the stop and bar being relatively adjustable; and means to retain the stop and abutment in coöperative position; of a minutely adjustable space bar shiftably with the carriage; and means to disable the tabulating stop bar and its stop, and by engagement with the minutely adjustable space bar, to lock the carriage where adjusted.
16. The combination with a traveling carriage; a stationary abutment; a tabulating stop bar shiftably mounted on the carriage; a stop carried on the bar, and adapted to coöperate with the abutment, the stop and bar being relatively adjustable; and means to retain the stop and abutment in coöperative position; of a minutely adjustable space bar connected with the tabulating stop bar; a pivotally mounted dog; and a lever operable upon the dog to force the latter against the minutely adjustable space bar to disable the tabulating stop bar and its stop, and to lock the carriage where adjusted.
17. The combination with a traveling carriage; a stationary abutment; a tabulating stop bar shiftably mounted on the carriage; a stop carried on the bar, and adapted to coöperate with the abutment, the stop and bar being relatively adjustable; and means to retain the stop and abutment in coöperative position; of a minutely adjustable space bar connected with the tabulating stop bar; a movable dog having an inclined face; means to normally hold the dog in one position; and means acting upon the inclined face, to force the dog to another position to disable the tabulating bar and its stop, and lock the carriage where adjusted.
18. The combination with a traveling carriage; a stationary abutment; a tabulating stop bar shiftably mounted on the carriage; a stop carried on the bar, and adapted to coöperate with the abutment, the stop and bar being relatively adjustable; and means to retain the stop and abutment in coöperative position; of a minutely adjustable space bar connected with the tabulating stop bar; a movable dog having an inclined face; means to normally hold the dog in one position; and a lever having a follower adapted to ride along the inclined face to force the dog to another position, to disable the tabulating bar and its stop, and lock the carriage where adjusted.
19. The combination with a traveling carriage; a stationary abutment; a tabulating stop bar shiftably mounted on the carriage; a stop carried on the bar, and adapted to coöperate with the abutment, the stop and bar being relatively adjustable; and means to retain the stop and abutment in coöperative position; of a minutely adjustable space bar connected with the tabulating stop bar; a movable dog having an inclined face; means to normally hold the dog in one position; and a lever having a follower adapted to ride along the inclined face to force the dog to another position, to disable the tabulating bar and its stop, and lock the carriage where adjusted, the inclined face terminating in a seat entered by the follower to retain the dog in the last mentioned position.
20. The combination with a traveling carriage; a stationary abutment; a tabulating stop bar shiftably mounted on the carriage; a stop carried on the bar, and adapted to coöperate with the abutment, the stop and bar being relatively adjustable; and means to retain the stop and abutment in coöperative position; of a minutely adjustable space bar connected with the tabulating stop bar; and a dog operable upon the minute space bar to disable the tabulating stop bar and its stop, and to lock the carriage where adjusted; said space bar and dog being provided with means which coact to prevent displacement of the carriage, during the disabling of the tabulating bar and its stop.
21. The combination with a traveling carriage; a stationary abutment; and a tabulating mechanism shiftably mounted on the carriage, to coact with the abutment; of a minutely adjustable space bar; a dog adapted to coact with the last named space bar to lock the carriage at any point in its travel; and a single means to release the tabulating mechanism from the abutment when the dog is in idle position, or to release the minutely adjustable space bar from the dog when the dog is in active position.
22. The combination with a traveling carriage; a stationary abutment; and a tabulating mechanism shiftably mounted on the carriage to coact with the abutment; of a minutely adjustable space bar; a dog normally in idle position, and shiftable to position to coact with the minutely adjustable space bar and lock the carriage where adjusted; and means to release the minutely adjustable space bar from the dog when the dog is in active position, to enable the adjustment of the carriage, relatively thereto.
23. The combination with a traveling carriage; and a stationary abutment, relatively

to which the carriage travels; of a toothed tabulating bar mounted on the carriage; a stop having teeth to engage the teeth on the tabulating bar, and adapted for movement transversely of the bar to disengage the stop teeth from the teeth on the bar, and permit a relative adjustment of the stop and bar; means to maintain the engagement between the teeth on the stop and those on the bar; and a laterally projecting tooth on the stop to engage the abutment and thereby arrest the carriage, the abutment being of sufficient area to maintain such engagement throughout the transverse movement 15 of the stop on the bar.

24. The combination with a traveling carriage; and an abutment, relatively to which the carriage travels; of a toothed tabulating bar mounted on the carriage; a stop having 20 teeth to engage the teeth on the tabulating bar, and adapted for movement transversely of the bar to disengage the stop teeth from the teeth on the bar, and permit a relative adjustment of the stop and bar; means to maintain the engagement between the teeth on the stop and those on the bar; a laterally projecting tooth on the stop to engage the abutment, the abutment being of sufficient area to maintain such engagement throughout the transverse movement 25 of the stop on the bar; and a finger hold formed on the stop to facilitate the disengagement of the stop teeth from the tabulator teeth, and enable the stop to be held released.

25. The combination with a carriage; and an abutment relatively to which the carriage travels; of a toothed tabulating bar mounted on the carriage; a tabulating stop, including a yoke loosely embracing the bar, for transverse movement relatively thereto; a toothed member secured between the arms of the yoke to mesh with the toothed bar; a guard plate slidably mounted between the

arms of the yoke; a spring interposed between one end of the yoke and the guard plate, to press the guard plate against one face of the bar, to maintain the toothed member engaged with the bar, and a tooth on the yoke to coact with the abutment. 45

26. The combination with a carriage; and a stationary abutment relatively to which the carriage travels; of a tabulating bar mounted on the carriage; a stop on the bar, the stop and bar being relatively adjustable; interlocking means between the stop and bar to hold the stop in adjusted position thereon; the stop adapted for movement transversely of the bar to release it therefrom; and a tooth on the stop to engage the abutment and thereby arrest the carriage, the tooth adapted to maintain its engagement therewith throughout its transverse movement relatively to the bar. 60

27. The combination with a traveling carriage; of a space bar shiftably mounted on the carriage; means to hold the bar at one end of its travel; a dog shiftable into and out of engagement with the bar to lock the carriage and bar where adjusted; and means 70 to shift the bar to the opposite limit of its travel to release the carriage and bar from the dog when the latter is in effective position, to enable the adjustment of the carriage relatively to the dog. 75

28. The combination with a traveling carriage; of a space bar shiftably mounted on the carriage; means to yieldingly hold the space bar at one end of its travel; a dog to releasably engage and partially shift the bar 80 against the action of the yielding means to hold the carriage where adjusted; and means to shift the bar to its opposite limit of travel to release the carriage for adjustment relatively to the dog when the latter is in effective position. 85

ARTHUR PENTECOST.
